CLAIM

The ornamental design for a ice cube maker, as shown and described.

DESCRIPTION

FIG. 1 is a perspective view of a ice cube maker showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an embodiment in which the ice cube maker is that it shows a state that can be used with the lid and can be opened thereof.

The broken lines depict portions of the ice cube maker that form no part of the claimed design.

1 Claim, 9 Drawing Sheets
